UNITED STATES PATENT OFFICE.

PHILIP M. HOWSE, OF NASHVILLE, TENNESSEE, ASSIGNOR TO HOL-FAST BEDLOCK COMPANY, OF NASHVILLE, TENNESSEE, A CORPORATION OF TENNESSEE.

SIDE-RAIL FASTENER FOR BEDS.

Application filed May 5, 1927. Serial No. 189,055.

This invention relates to furniture and more particularly to a fastener by means of which side rails of a bed may be secured to the head and foot posts of the bed.

5 At the present time it is customary to provide the side rails of a bed with hooks which project from the ends thereof and are intended to be fitted into slots formed in the head and foot posts where they engage pins extending transversely through the slots. This has been found unsatisfactory as the hooks become tightly wedged between the cross pins and inner ends of the slots and it is very difficult to release 10 the hooks. It is often necessary to strike the under portion of the side rail with a hammer or the like in order to release the hooks and this is liable to mar the side rail or break it if formed of metal.

20 Therefore, one object of the invention is to provide a bed rail fastener which may have portions engaged with cross pins passing through a slot in a bed post and very securely held in engagement with the pins 25 but permitted to be easily released therefrom.

Another object of the invention is to provide the fastener with a body portion adapted to be secured to a bed rail and upon the 30 body mount levers carrying arms to engage the cross pins of a bed post, means being provided to securely but releasably retain the levers in a set position.

Another object of the invention is to permit the levers to be mounted upon a common pivot pin and also mount securing means upon the pin which will serve to retain the levers thereon and to securely hold them in a set position.

40 Another object of the invention is to guide movement of the pin engaging arms so that they may be easily engaged with or disconnected from the cross pins carried by the bed posts.

45 Another object of the invention is to provide a fastener of the character described which may be formed from stamped sheet metal and, therefore, strong and durable at the same time cheap to produce.

50 The invention is illustrated in the accompanying drawing, wherein.

Figure 1 is a view showing one end portion of a bed rail connected with a portion

of a bed post by one of the improved fasteners, the view being principally in side elevation but partially in section;

55 Fig. 2 is a longitudinal sectional view taken on the line 2-2 of Fig. 1;

Fig. 3 is a fragmentary view showing a portion of one of the levers constituting a 60 part of the fastener, and

Fig. 4 is a side elevation illustrating a modified form of fastener.

The fastener constituting the subject-matter of this invention is intended to connect a side rail 1 of a bed with a post 2 forming a portion of the head or foot of the bed and includes a body portion 3 which is preferably formed from stamped sheet metal and may be provided with ears 4 and 5 extending from its sides and one end so that the body may be seated in a recess 6 formed in the bed rail and screws or equivalent fasteners 7 passed through the ears and into the bed rail to securely hold the body in place. If desired, the ears 4 and 5 may be omitted and the body or bracket 3 disposed flat against the inner face of the bed rail and the fasteners passed through

75 openings formed adjacent the margins of the bracket, as shown in Fig. 4. By having the bracket seated in a recess formed in the bed rail as shown in Figs. 1 and 2, it will be countersunk and elements carried by the bracket will be shielded and thereby prevented from being damaged. A flange 8

80 extends across the outer end of the bracket or body 3 and this flange is formed with spaced slots or openings 9 through which pass arms 10 having hooks 11 at their outer ends. These arms project from the end of the bed rail and are intended to be passed into a recess or pocket 12 formed in a bed post 2 and engaged with pins 13 which are carried by the post and extend transversely through the pocket, as shown in Fig. 2.

90 In order to actuate the arms 10, there has been provided levers 14 which are pivotally mounted upon a stem 15 carried by and extending transversely from the bracket 3 adjacent the outer end thereof. Each lever has its pivotally mounted end provided with a side extension 16 to which an arm 10 is pivotally connected by a rivet or equivalent fastener 17 and about the pivot stem 15 the levers are formed with

teeth 18 which interlock when the winged nut 19 is tightened so that the levers may be securely held in a set position.

When the fastener is in use, it is applied 5 to a bed as shown and the arms 10 project from the side rail through the openings formed in the flange 8 of the bracket 3. The arms are passed into the pocket 12 above the cross pins 13 and the side rail of the bed 10 is then allowed to move downwardly until the arms rest upon the cross pins. The levers are then grasped and pressure applied 15 to move them toward each other from the position shown in Fig. 4 towards the position shown in Fig. 1. This movement causes the side extensions of the levers to swing away from the flange 8 and the arms 10 will be moved longitudinally until their 20 hooks 11 are in firm engagement with the pins 13 and the flange 8 and end face of the bed rail held in close contacting engagement with the bed post. The winged nut 19 is now tightened upon the stem 15 and will bear against the levers to hold the 25 teeth 18 in interlocked engagement and prevent the levers from returning to the position shown in Fig. 4. Therefore, the bed rail will be very securely held in engagement with the bed post. When it is desired 30 to release the rail, it is merely necessary to loosen the nut and the levers can then be swung away from each other. This will cause the hooked ends of the arms to be moved away from the pins carried by the 35 bed posts and the rail may be easily lifted and the arms drawn out of the recess in the post. It will thus be seen that with this fastener a bed rail may be very securely held in engagement with a bed post but may 40 be very easily released when necessary. It should be noted that the levers are movable independently of each other and, therefore, are self-equalizing as each hook 11 may be drawn into tight gripping engagement with 45 its pin 13 even if the pins are not disposed evenly in the recess and a very tight joint formed between the posts and side rails of a bed.

Having thus described the invention, I 50 claim:

1. A fastener comprising a body adapted to be secured to an article to be supported, a flange extending transversely from said body and formed with slots, a stem extending 55 from said body, levers pivotally carried by said stem and having handle portions movable towards and away from each other, arms pivotally connected with said levers and extending through said slots and having 60 their outer end portions provided with support-engaging means, and means carried by said stem to releasably secure the levers in a set position.

2. A fastener comprising a body adapted 65 to be secured to an article to be supported,

a flange extending transversely from said body and formed with slots, a stem extending 70 from said body, levers pivotally carried by said stem one against the other and having handle portions movable towards and away from each other, arms pivoted to said levers at opposite sides of the stem and slidably passed through the slots of said flange and having their outer end portions provided 75 with support-engaging means, and means carried by said stem to releasably secure the levers in a set position.

3. A fastener comprising a body adapted 80 to be secured to an article to be supported, a flange extending transversely from said body and formed with slots, a stem extending from said body, levers pivotally carried by said stem one against the other and having handle portions movable towards and away from each other, arms pivoted to said 85 levers at opposite sides of the stem and slidably passed through the slots of said flange and having their outer end portions provided with support-engaging means and a securing nut for said levers threaded upon 90 said stem.

4. A fastener comprising a body adapted 95 to be secured to an article to be supported, a stem extending from said body, levers pivotally mounted upon said stem and having handle portions movable toward and away from each other, arms pivoted to said levers and having their outer end portion adapted to engage a support, and means carried by said stem to releasably secure the 100 levers in a set position with the arms in firm engagement with a support.

5. A fastener comprising a body adapted 105 to be secured to an article to be supported, a flange extending transversely from said body and formed with slots spaced longitudinally of the flange, a stem extending from said body, levers pivoted upon said stem and having handle portions movable towards and away from each other, said levers having side extensions extending from opposite 110 sides of said stem and contacting faces of the levers about the stem having interlocking teeth, arms pivoted to the side extensions of said levers and slidably passed 115 through said slots and having their outer ends provided with support-engaging hooks, and a securing nut threaded upon said stem and adapted to hold the levers in a set position with their teeth interlocked.

6. An article to be supported having a side face formed with a recess, a bracket seated in said recess, securing tongues extending from marginal portions of said bracket and engaging the walls of the recess with their end portions overlapping the said face of said article and secured thereto, a stem extending from said bracket and disposed in the recess, levers loose upon said 120 stem and extending longitudinally of the 130

bracket within the recess, arms carried by said levers and extending from the article through one end of the recess with their outer ends adapted to engage a support, and 5 means carried by said stem to hold the levers in a set position.

7. An article to be supported having a side face formed with a recess, a bracket seated in said recess and secured therein, 10 a stem carried by said bracket and disposed within the recess, levers pivoted upon said stem and extending longitudinally in the recess and movable towards and away from each other, arms pivoted to said levers and 15 projecting from the article through one end of the recess and having support-engaging means at their outer ends, and securing

means carried by said stem to releasably retain the levers in a set position.

8. A bed rail fastener comprising a body 20 adapted to be secured against a bed rail, levers disposed one against the other and at one end pivoted to said body, the pivoted ends of said levers being disposed about a common pivot and having side extensions 25 extending in opposite directions, anchors pivoted to the side extensions of said levers and projecting from the levers in vertical spaced relation to each other, means to support the anchors and guide movement thereof, and means to releasably retain the levers in adjusted positions.

In testimony whereof I affix my signature.
PHILIP M. HOWSE. [L. s.]
